PORTABLE WARNING DEVICE

Samuel Reuben, Jr., Chicago, Ill.

Application August 9, 1951, Serial No. 16,213

Term of patent 14 years

(Cl. D26—5)

To all whom it may concern:

Be it known that I, Samuel Reuben, Jr., a citizen of the United States, residing at Chicago, in the county of Cook and State of Illinois, have invented a new, original and ornamental Design for a Portable Warning Device, of which the following is a specification, reference being had to the accompanying drawing, forming a part hereof.

Fig. 1 is a perspective view showing the front, one side, and top of a portable warning device embodying my new design, with the reel, cord, low melting point fuse, connecting clip, electric cord and bell shown in dotted outline.

Fig. 2 is a perspective view showing the rear, one side, and top of the portable warning device of Fig. 1, with the reel, cord, and connecting clip shown in dotted outline.

The side of the portable warning device which is not shown in the drawings is identical with the side shown.

The dominant features of my design reside in the portions shown in full lines.

I claim:

The ornamental design for a portable warning device, substantially as shown and described.

SAMUEL REUBEN, JR.
